Primary Examiner — Mark A Goodwin*(74) Attorney, Agent, or Firm* — Westerman, Hattori,
Daniels & Adrian, LLP(57) **CLAIM**

The ornamental design for a front cover for lawn mower, as shown and described.

DESCRIPTION

FIG. 1 is a front and right perspective view of a front cover for lawn mower showing my new design;

FIG. 2 is a front and left perspective view thereof;

FIG. 3 is a rear and right perspective view thereof;

FIG. 4 is a rear and left perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof;

FIG. 10 is a bottom plan view thereof; and,

FIG. 11 is a front and right perspective view thereof.

The broken lines in the drawings illustrate portions of the front cover for lawn mower that form no part of the claimed design.
